United States Patent Office

Des. 205,058
Patented June 21, 1966

205,058

SHOE VALET CABINET

George L. Herbert, New York, N.Y., assignor to Merchants Box Company, Dallastown, Pa., a corporation of Pennsylvania

Filed July 21, 1965, Ser. No. 86,235

Term of patent 7 years

(Cl. D9—2)

FIG. 1

FIG. 3

FIG. 1 is a perspective view from one corner of the top of a shoe valet cabinet showing my new design.

FIG. 2 is a perspective view from one corner of the shoe valet cabinet shown in FIG. 1.

FIG. 3 is an elevational view from one side of the shoe valet cabinet shown in FIG. 1.

The side not shown has substantially the same appearance as the side shown. The rear not shown is like the front, except as indicated.

I claim:

The ornamental design for a shoe valet cabinet, substantially as shown and described.
